DESIGN FOR A COMBINED DOOR-HANDLE AND HOOK-BUMPER

Sterling H. Campbell and Frank H. Pietzsch, St. Louis, Mo., assignor to Western Railway Equipment Company, St. Louis, Mo., a corporation of Missouri

Application January 17, 1940, Serial No. 89,520

Term of patent 14 years

To all whom it may concern:

Be it known that we, Sterling H. Campbell and Frank H. Pietzsch, citizens of the United States of America, residing at the city of St. Louis, State of Missouri, have invented a new, original, and ornamental Design for a Combined Door-Handle and Hook-Bumper, of which the following is a specification, reference being had to the accompanying drawing, forming a part thereof.

In the drawing, Figure 1 is a side elevational

view of a combined door-handle and hook-bumper showing my new design; Figure 2 is a top plan view; Figure 3 is a section on the line 3—3 of Figure 1; and Figure 4 is a section on the line 4—4 of Figure 1.

We claim:

The ornamental design for a combined door-handle and hook-bumper, as shown.

STERLING H. CAMPBELL,
FRANK H. PIETZSCH.
